DESIGN FOR A WHEELED COASTER

Frank G. Birkhead, Philadelphia, Pa., assignor to
S. L. Allen & Co., Inc., Philadelphia, Pa., a corporation of Pennsylvania

Application January 2, 1937, Serial No. 66,861

Term of patent 14 years

To all whom it may concern:

Be it known that I, Frank G. Birkhead, a citizen of the United States, residing in Philadelphia, county of Philadelphia, and State of Pennsylvania, have invented a new, original, and ornamental Design for a Wheeled Coaster, of which the following is a specification, reference being had to the accompanying drawing, forming a part thereof.

In the drawing, Fig. 1 is a top plan view of a wheeled coaster, showing my new design, and Fig. 2 is a side elevation thereof.

I claim:

The ornamental design for a wheeled coaster substantially as shown.

FRANK G. BIRKHEAD.
